UNITED STATES PATENT OFFICE.

FRANK J. MATEY, OF GALESBURG, ILLINOIS.

GATE.

1,076,300.

Specification of Letters Patent.

Patented Oct. 21, 1913.

Application filed October 28, 1912. Serial No. 728,203.

To all whom it may concern:

Be it known that I, FRANK J. MATEY, a citizen of the United States, and a resident of Galesburg, in the county of Knox and State of Illinois, have invented a new and useful Gate, of which the following is a specification.

My invention relates to swinging gates, and particularly to that type or class thereof which may be bodily elevated to certain positions within limits, and there held in order to permit the passage of stock thereunder.

The principal object of the invention is to provide novel means on which the gate body may slide vertically and then, after being elevated to the desired height, will be automatically locked in its elevated position.

Another object is to provide means for hinging the gate, which means shall coöperate with those just recited.

To the attainment of these and the accomplishment of other objects, as will presently appear, the invention consists in the features of novelty in the details of construction, the arrangements and the combinations of the several elements hereinafter described in detail and shown in the accompanying drawings, as well as set forth in the appended claims.

While said drawings illustrate a preferred embodiment of the invention it is to be understood that I do not consider myself as limited to the precise structural details of all of the parts or elements shown and described, for it will be manifest that numerous unessential changes may be made in the details of construction without departing from the general idea of the invention, considered in its broadest aspect.

In said drawings: Figure 1 is an elevation, showing all of my improvements as embodied therein; Fig. 2, a similar view, showing a portion of the gate sustained in one of its elevated positions; Fig. 3, an enlarged vertical sectional detail, partly in elevation; Fig. 4, an enlarged, fragmental, sectional detail, partly broken away, the view taken at a right angle to Fig. 3; Fig. 5, a modification, an enlarged sectional detail; Fig. 6, a top plan, broken away; and Fig. 7, a fragmental detail, an elevation.

Considering said drawings by numerals, the same one of which is uniformly employed in referring to the same element, 2 designates a supporting post into which

are screwed the stems 3 of pintle-receiving eyes 4.

5 designates a collar provided in its upper face with a groove 6, Fig. 3. Said collar fits over the stem 7 of a pin 24 having a threaded portion 8, and may be shrunk or welded onto said stem, or, if preferred, integral therewith, as a flange.

9, 9 designate the eyes of pintle-receiving hinge members 10 secured to the upper and lower gate slats 11 by bolts 12 or in any other suitable manner.

The same numeral —12— is employed to designate the securing bolts for the braces, 70 slats and standards.

Either or both of the elements 10 may be provided with a lug 13 which, when the gate is in its closed position, is adapted to drop into the groove 6 in the collar 5 to 75 prevent the gate from blowing open.

14 is a tubular pintle which passes through the upper eye 4 and through both eyes 9, and its base receives the pin stem 7 and rests on the collar 5. It 80 is provided with a selective number of oppositely arranged coincident slots 15 in its walls. Hinged at their lower ends by a pin 17 secured in the walls of the pintle 14 by a pin 17 having a bushing 18 are pairs of 85 gate-supporting dogs 19, the free ends of which lie, when in normal positions, through the slots 15, but when the lower eye 9 is elevated it will force said ends back until their upper outer corners lie flush with the outer surface of the pintle, and when said eye has cleared said corners the dogs will fall back into their normal positions and upon the gate being released the lower eye 9 will engage the upper edges of that 90 pair of dogs which is next below it and the gate will be sustained thereby in an evident manner. To lower the gate therefrom it is necessary only to press the free ends of the dogs inwardly. The eyes 9 will turn on the 100 pintle 14 to swing the gate in the usual manner.

25 is a cap on the pintle.

26 is a locking nut.

In connection with the novel features I 105 have in the accompanying drawings illustrated a gate body which includes standards 20 each of which has a centrally and longitudinally arranged rib 21. Portions of these ribs may be omitted where necessary, 110 as shown in Fig. 1. Following up the purpose of rigidity I provide a longer diag-

onally arranged truss or brace member 22 which is preferably secured to the inner standard, the top board, and to at least two of the other standards. A similarly arranged brace member, 23, is secured at one end to the inner standard and lower board and its diagonally disposed portion is secured to one of the standards but preferably not to the other truss member. I thus not only allow the strength of an entire bolt to be utilized for each brace at their convergence, but I avoid the element of danger of non-coincident prepunched holes.

A modification of one of the truss members is shown in Fig. 7, and a modification of the supporting dogs is shown in Fig. 5.

Having thus described my invention, and having set forth its uses, purposes and advantages, I claim as new and desire to secure by Letters Patent the following, namely:

1. Combined in a gate, a body, means on which it may have both vertical and swinging movements, and pintle-carried hinged dogs adapted to lock the said body in elevated position.

2. Combined in a gate, a body, a pintle on which it may rise, fall, and swing, and dogs hinged to said pintle and adapted to support the gate in elevated position.

3. Combined in a gate, a body, a tubular pintle on which it may have vertical and swinging movements, said pintle provided with a slot, and a dog hinged to said pintle and adapted in one position to be forced back into the tubular portion thereof and in another position to swing outward and provide a support for the gate when it is elevated.

4. In combination with a gate body, apertured hinge members secured thereon, a tubular pintle seated loosely in the apertures in said hinge members and the latter adapted to have both vertical and swinging move-

ments on said pintle, a dog hinged to said pintle and adapted in one position to be forced into the hollow thereof, and in another position adapted to support the gate body when it is in elevated position, and means for supporting said pintle.

5. In combination with a gate body, apertured hinge members secured thereon, a pintle seated loosely in the apertures in said hinge members and the latter adapted to have both vertical and swinging movements on said pintle, a dog hinged to said pintle and adapted to support the gate body when it is in elevated position, and means for supporting said pintle.

6. In combination with a gate-body, apertured hinge-members secured thereon, an apertured hinge-member securable to a post, a tubular pintle on which the first recited hinge members are adapted to rise, fall, and swing, means for supporting its lower end, and dogs hinged to said pintle and adapted in one position to be forced back into the hollow thereof and in another position to swing outwardly to provide a support for the gate body when it is elevated.

7. In combination with a gate body, apertured pintle-receivers secured thereon, an apertured pintle-receiver adapted for securement to a post, a tubular pintle seated in the apertures in said receivers, a supporting element secured to the lower portion of the gate, a pin supported thereby and adapted to be received in the aperture in the lower end of the pintle, and dogs hinged to said pintle and adapted to support the gate when it is elevated.

In testimony whereof I hereto sign my name in presence of two subscribing witnesses.

FRANK J. MATEY.
